UNITED STATES PATENT OFFICE.

ELIZABETH CHAVERS, OF SIDDON, MICHIGAN.

SEWING-MACHINE SHUTTLE.

SPECIFICATION forming part of Letters Patent No. 281,453, dated July 17, 1883.

Application filed February 26, 1883. (No model.)

To all whom it may concern:

Be it known that I, ELIZABETH CHAVERS, of Siddon, Mason county, Michigan, have invented a new and Improved Shuttle for Sewing-Machines, of which the following is a full, clear, and exact description.

The object of my invention is to provide a new and improved shuttle for sewing-machines, which shuttle is to be so constructed that it can hold any spool of thread or silk.

The invention consists in a shuttle adapted to receive a spool of thread or silk, which spool is mounted on a spindle held in the shuttle and screwed in a screw-cap on one end of the shuttle, the thread of which spool is then passed through an aperture or slot in the shuttle, through a U-shaped slot in a blade pivoted on the shuttle, and through an opening in the said blade, and is then passed through the opening in the sewing-plate of the machine.

Reference is to be had to the accompanying drawings, forming a part of this specification, in which similar letters of reference indicate corresponding parts in all the figures.

Figure 1 is a longitudinal elevation of my improved bobbin-holder or shuttle. Fig. 2 is a longitudinal sectional elevation of the same on the line *x x*, Fig. 1. Fig. 3 is a cross-sectional elevation of the same on line *y y*, Fig. 2.

The shuttle A is constructed hollow, and is provided at one end with a threaded neck, B, on which an internally-threaded cap, C, is adapted to be screwed, in which cap the spindle D is screwed, and on which spindle the spool F is loosely mounted. The spindle D passes longitudinally through the shuttle, and has its end passed into the end plate, E, of the shuttle, which end plate, E, can be fastened in the shuttle by means of any suitable spring de-

vice. The spool F is held on the spindle D 40 by means of washers G G, or other like or suitable fastenings. On the shuttle a blade, H, is pivoted, which is provided with a U-shaped slot, J, and with an aperture, K. The shuttle is provided with a longitudinal slot, 45 L. A spring-clip, M, serves to hold the free end of the blade H in the desired position. The shuttle is provided with two lugs, N N, for holding it in position in the shuttle-race. The thread *a* is passed through the slot L, through 50 the two longitudinal parts of the U-shaped slot J—that is, under the tongue formed by the said slot—and then under the blade H, through the aperture K, and is then passed through the aperture in the sewing-plate. The 55 screw-cap C holds the spindle D in place, and by removing the screw-cap the spindle can be withdrawn. The end plate, E, is removed when a spool is to be placed in the shuttle. The usual bobbins are not used, and the time generally wasted in winding the bobbins is saved.

Having thus described my invention, I claim as new and desire to secure by Letters Patent—

1. In sewing-machine shuttles, the combination of a screw-cap, C, centrally apertured and threaded, a spindle, D, threaded at one end, and an externally-threaded neck to receive the cap, whereby the spindle may be held and released, as described.

2. The combination, with the shuttle A, of 70 the spindle D, the screw-cap C, into which the spindle is screwed, and the removable end plate, E, substantially as herein shown and described, and for the purpose set forth.

ELIZABETH CHAVERS.
